8092X

A. COFFMAN.
EARTHEN TUBE MACHINE.

Patented Mar. 18, 1834.

Andrew Coffman of New Market, Virginia
Selles Patent

The Schedule referred to in the Sells Patent and making part of the
same containing a description in the words of the said Andrew Coffman
himself of his improvement in the machine for making stone or earthen
piping for the conveyance of water &c.

To all to whom these presents shall come, Be it known that I,
Andrew Coffman of New Market in the County of Shenandoah,
State of Virginia, have invented a new method of making clay or
stone tubes or pipes for the conveyance of water &c by means of a press
and mould, and that the following is a full and exact description
of the construction and operation of the same. The press consists of
a bench of thick Planks 3 $\frac{1}{2}$ feet long and 17 or 18 inches wide, sup-
ported on four posts or legs of any convenient height. About 9 inches
from each end are two mortices in which are framed two uprights,
the tenons to extend through the bench to admit being secured by pins
or pins. Said uprights to be about 6 inches wide 2 $\frac{1}{2}$ thick & stand
above the bench about twelve inches to a cross piece through which is
a 2 $\frac{1}{2}$ inch wooden screw worked by a lever at the upper end of said
screw. The mould consists of two clay blocks about 3 feet long, 6
inches wide & 5 thick, one side is worked to a semi cylindrical hollow
of about 3 inches diameter to within 2 inches of one end where the di-
ameter is half an inch less, which moulds a round tenon on the end
of the tube, the corners of the hollow blocks are chamfered to an angle
of 45° making the edge between the angle & hollow nearly sharp (to
admit the superfluous clay being pressed out) on each side of the hollow blocks
about 6 inches from each end are iron dowels with corresponding holes
in the other block to receive the end of said pins to keep the hollow blocks
in their proper place so as to form a perfect cylindrical hollow to be covered
with sheet copper or other suitable metal, on each end of said blocks
are bearings to support the ends of a staff turned of metal or some fine
grained wood such as cedar applying clay & said staff is three feet

Mar 18, 1834

fat eight inches long one end extends beyond the ends of the hollow blocks, and is about 4 inches in diameter the head terminates by a square shoulder towards the longest end of the staff joining the head. The diameter is $2\frac{1}{4}$ inches & 2 inches long to form a socket to receive the other end of the tube, then another offset reduces it to $1\frac{3}{4}$ inch at the largest end, the other end is about $\frac{1}{8}$ inch tapering from the said offset in a straight line. Operation. After the clay is properly tempered and cut in sheets of $5\frac{1}{2}$ inches wide 36 inches long and $\frac{3}{8}$ inch thick, take two sheets and lay them in the hollow block and lap join them in the bottom of the hollow. then lay on the staff and join the two sheets of clay on top. then put on the other hollow block. take it to the press and force the two blocks together and force out all the superfluous, loose the screw, turn the staff and take it from the mould.

For further illustration of my invention I refer to the drawing model of the same deposited in the Patent office. What is herein claimed as my invention is the construction of the mould and the application of the said pipes in the manner above specified for the conveyance of water by stone or earthen pipes. In witness that therefore is a true specification I have hereunto subscribed my name at the town of New Market Shenandoah County and State of Virginia this

1st day of March 1834.
